UNITED STATES PATENT OFFICE.

HALBERT B. HALVORSEN, OF MICHIGAN CITY, INDIANA, ASSIGNOR TO SULLIVAN MACHINERY COMPANY, A CORPORATION OF MASSACHUSETTS.

FORGING MACHINE.

Application filed April 20, 1925. Serial No. 24,419.

This invention relates to forging machines. In forging machines of the type herein disclosed which is particularly useful for forming coal mining machine cutter bits, it is desired to utilize the forging heat of the bit blank for tempering purposes after the blank has been formed into a complete bit. During a normal forging operation the cutting portion of the bit which is relatively thin is cooled, due to contact with the cold forging die, while the shank of the bit retains considerable heat. To utilize this heat for tempering purposes it is necessary to allow a sufficient length of time for distribution of the heat in the shank to the cutting portion after which the bit can be discharged into the tempering bath. This holding or heat distribution operation takes place after the formed bit has been discharged from the zone in which the forging die operates thus permitting another bit to be forged during said holding operation. An object of the invention is accordingly to provide improved means for allowing distribution of the forging heat for tempering purposes. A further object is to provide improved means whereby sufficient time will be obtained for allowing this heat distribution and specifically to have said means automatically controlled by or coordinated with some operation of the machine. A still further object is to provide improved means whereby two phases of this latter operation will be involved thereby providing a suitable length of time for heat distribution. A more specific object of the invention is to provide a double baffle arrangement whereby the bit upon initial discharge from the forging machine will be interrupted and then upon operation of the forging machine to forge another bit the first bit will move further, only to be interrupted by a second baffle, and then upon discharge of the second bit the last baffle will be operated to allow discharge of the first bit into its bath. A further specific object of the invention is to have said baffles controlled by the foot treadle controlling the operation of the forging die.

In the accompanying drawings I have shown for purposes of illustration one form which my invention may assume in practice.

In these drawings,—

Fig. 1 is a side elevation of a forging machine with my improved means attached thereto.

Fig. 2 is an end elevation of the machine, partly broken away to show details of construction.

Fig. 3 is a vertical longitudinal section of a portion of the forging machine showing the forging roller and blank holder.

Fig. 4 is an end fragmentary elevation of the double baffles.

Fig. 5 is a sectional view of the baffles shown in a position as in Fig. 4, taken on line 5—5 of Fig. 1.

In the illustrative embodiment of my invention I have shown a machine of the type which is the invention of one Harry C. Johansen, Pat. No. 1,604,414, and comprises a frame 1 mounted upon suitable standards or legs 2 and having a belt driven fly wheel 3 adapted to reciprocate a suitable crosshead 4 slidably mounted in a horizontal plane in the front end of the frame 1. This crosshead carries a clapper box mounted forging roller 5 having a uniform annular groove 6 adapted to form the cutting portion 7 of a cutter bit 8 which is held during the forging operation in a suitable combined discharge and holding mechanism 9. Upon completion of the forging operation the mechanism 9 will be laterally shifted by a suitable hand operated lever 11 to allow discharge of the bit through an opening 10 upon a chute 12 leading to the outer side of the front leg 2.

My invention for interrupting movement of the bit is herein specifically located at the end of the chute 12 and comprises a baffle 14 having trunnions held in slots 15 of brackets 16 formed on the side of the leg 2 and held by pins 17. Disposed immediately below said baffle is a second baffle 18 of substantially greater length and supported in a bracket 19 similar to the bracket 16. A lug 20 is formed on the end of the baffle 18 adjacent the trunnions thereof, while fixed to one of the trunnions on the outer side of the bracket 19 is a gear segment 21 adapted to have engagement with a second gear segment 22 fixed to one of the trunnions of the baffle 14, it being noted from Fig. 5 that the baffles 14 and 18 are normally angularly disposed and that the same will always retain an angular relation during relative movement therebetween. Carried by the segment 22 is an arm 23 having an opening 24 adapted to loosely receive a rod 25 having nuts 26 thereon to form a suitable operating connection for actuating the baffles, it being

noted that the surface of the arm 23 adjacent the opening 24 is rounded as at 27 thereby always to have the nuts 26 in contact with the arm 23 and prevent any excessive lost motion during operation. A foot treadle 28 to which the lower end of the rod 25 is pivotally connected has an upwardly extending arm 29 to which is pivotally connected a clutch operating rod 30 for controlling reciprocity of the crosshead 4 by the fly wheel 3.

In operation, after the bit blank has been inserted within the holding mechanism 9, forging of the bit will be controlled by 15 pressing down the treadle 28 which will cause also downward movement of the rod 25 with consequent movement of the baffles 14 and 18 to the dotted line positions shown in Fig. 5. Assuming that this bit has not 20 been discharged, the operator upon releasing the treadle 28 to its full line position shown in Fig. 1 will then operate the discharge lever 11 and cause the bit to be discharged, whereupon it will strike the baffle 14 and 25 come to rest. Upon insertion of a second blank, downward movement of the treadle 28 will as before stated drop the baffle 14 and allow the bit to move against the now upwardly extending baffle 18, this operation 30 taking place during the forging operation of the second bit. The baffle 18 is of course held in its upwardly extending position by the operator holding down the treadle 28. The lug 20 will also prevent a bit from sliding 35 down against the leg 2 and becoming jammed in any way or discharging through the back. Upon release of the treadle 28 the second baffle will permit the bit to readily slide into a tempering bath contained 40 within a receptacle disposed immediately below the baffle 18. It will thus be seen that I have provided improved means whereby the 45 discharge of a bit into a tempering bath from a forging machine is delayed a sufficient length of time and herein equal to a complete cycle of operation of the forging die.

While I have in this application specifically described one form which my invention may assume in practice, it will be understood that this form has been shown for purposes of illustration and that the invention may be modified and embodied in various other forms without departing from its spirit or the scope of the appended claims.

55 What I claim as new and desire to secure by Letters Patent is:

1. In combination, a bit sharpening machine having bit ejecting means, and means for twice interrupting movement of said bit after leaving the ejector but before leaving the machine.

2. The combination with a forging machine having bit ejecting mechanism, and means operable during a plurality of operations of an element of said machine for

interrupting movement of a bit from said machine during each operation after being ejected.

3. In combination, a bit sharpening machine having bit ejecting means, means for controlling a plurality of operations of said machine, and means operable during a plurality of said operations for interrupting movement of an ejected bit controlled by said controlling means. 75

4. The combination with a forging machine having an ejecting mechanism for a work piece, and means operable upon an ejection operation to successively interrupt movement of an ejected work piece 80 before discharge thereof is completed.

5. A forging machine having means for controlling an ejected work piece comprising a plurality of relatively movable elements adapted to successively interrupt movement 85 of said work piece before discharge thereof is completed.

6. A forging machine having means for controlling an ejected work piece comprising a plurality of movable elements, one being adapted to be moved to discharge a work piece therefrom upon the other and to allow said other element to hold the work piece and thereafter allow the same to be discharged. 95

7. A forging machine having means for interrupting movement of an ejected work piece comprising a plurality of angularly movable baffle plates, said plates being so arranged that if extended during successive 100 operations they would intersect on opposite sides of a common line.

8. A forging machine having means for controlling an ejected work piece comprising a plurality of baffle plates for successively 105 retarding movement of said work piece from said machine.

9. A forging machine having means for controlling an ejected work piece comprising a plurality of angularly movable baffle 110 plates connected by gears.

10. A forging machine having means for controlling an ejected work piece comprising a plurality of angularly movable gear connected baffle plates, and actuating means 115 connected to one of said plates adapted to actuate both of the same.

11. A forging machine having means for controlling an operation thereof, means for controlling an ejected work piece comprising a plurality of angularly movable gear connected baffle plates, and means for controlling said plates by said means which controls said operation. 120

12. A forging machine having means 125 adapted to control movement of an ejected work piece from said machine comprising a plurality of means adapted to successively control movement of the work piece.

13. A forging machine comprising die op- 130

erating mechanism, means for ejecting forgings from the machine including a chute, means for delaying the ejection of said forging comprising a pivoted member for blocking said chute, control means for said operating mechanism, and a rigid adjustable link member for connecting said control means and pivoted member whereby said chute is opened and closed by operation of said control means.

14. A forging machine comprising die operating mechanism, means for ejecting forgings from the machine including a chute, means for delaying the ejecting action to permit redistribution of heat in the forging, means associated with said delaying means for allowing final ejecting movement of said forging only after completion of a forging operation on the next succeeding forging.

15. A bit sharpening machine comprising mechanism for forming heated bits, means for controlling said mechanism, means for ejecting forgings from the machine including a chute, means for interrupting movement of said bit from said chute until a forging operation on the next succeeding bit is started, and other means for further delaying said movement during the forging operation on said succeeding bit.

16. A bit sharpening machine comprising mechanism for forging heated bits, control means for said mechanism, means for ejecting forgings from the machine including a

chute, a baffle plate adapted to be operated by movement of said control means for interrupting movement of a bit from said chute, and a second baffle plate for further interrupting movement of said bit after being discharged from said first baffle plate, said second baffle plate also being operated by movement of said control means.

17. In a forging machine, a die, die operating mechanism, controlling means therefore, work piece holding and discharging means, and means for delaying discharge, to permit redistribution of heat in a finished work piece, including means for effecting discharge only upon a complete cycle of operation of the controlling mechanism for the die operating mechanism subsequent to the completion of the operation of the die upon the work piece.

18. In a forging machine, a die, die operating mechanism, work piece holding and discharging means, and controlling means including a lever movable to effect forging of a work piece, and means for delaying discharge to permit redistribution of heat in a finished work piece including means for effecting discharge only upon a complete cycle of operation of said lever subsequent to the completion of the operation of the die upon the work piece.

In testimony whereof I affix my signature.

HALBERT B. HALVORSEN.
